UNITED STATES PATENT OFFICE.

JOHN CISON, OF WAUSAU, WISCONSIN.

HYDROPLANE.

1,391,368.

Specification of Letters Patent. Patented Sept. 20, 1921.

Application filed November 24, 1920. Serial No. 426,218.

To all whom it may concern:

Be it known that I, JOHN CISON, a citizen of Poland, residing at Wausau, in the county of Marathon and State of Wisconsin, have 5 invented certain new and useful Improvements in Hydroplanes, of which the following is a specification.

This invention relates to certain new and useful improvements in hydroplanes and has 10 for one of its objects to provide a machine as well adapted for air travel as in water.

A further object of the invention is to provide a hydroplane equipped with a plurality of parachute members that are inoperatively 15 positioned when the machine is traveling through air and capable of shifting to operative position during descending movement of the machine to cause the same to gradually alight upon the surface of the 20 water and also for safety purposes.

A still further object of the invention resides in the provision of a hydroplane having a superposed deck or gangway mounted by the provision of a ladder construction for 25 purposes of observation.

With the above general objects in view and others that will appear as the nature of the invention is better understood, the same consists in the novel form, combination and 30 arrangement of parts hereinafter more fully described, shown in the accompanying drawings and claimed.

In the drawings, wherein like reference characters indicate corresponding parts 35 throughout the several views,

Figure 1 is a side elevational view of a hydroplane constructed in accordance with the present invention showing the parachute attachments therein in their operative posi- 40 tions.

Fig. 2 is a top plan view showing the parachutes open to operative position with the superposed deck positioned above the parachutes,

Fig. 3 is a side elevational view similar to Fig. 1 showing the parachutes folded to in- 45 operative position,

Fig. 4 is a fragmentary side elevational view, partly in section showing the tubular 50 posts for supporting the parachute sections,

Fig. 5 is a cross sectional view taken on line V—V of Fig. 4 showing the rib connec- 55 tions between the parachute and the tubular support therefor,

Fig. 6 is a horizontal sectional view taken on line VI—VI of Fig. 7 showing the rope

drum within the tubular support for operating the parachute, and

Fig. 7 is a fragmentary side elevational view of one of the tubular supports for a 60 parachute section showing the pawl and ratchet for holding the parachute opened in its operative position.

Referring more in detail to the accompanying drawings there is illustrated a 65 hydroplane embodying a passenger body 1 having side windows 2 and a side rail 3 upon the deck portion thereof. The propeller 4 at the forward end of the body 1 is driven by suitable motor mechanism con- 70 tained within the body.

An observation deck is carried by the passenger body 1 and is carried by tubular supports 5 extending perpendicularly from the body 1, the observation deck including a 75 propeller 6 having side rails 7 and being forwardly declined as shown in Figs. 1 and 3. A ladder construction 8 extends from the rear end of the platform 6 to the rear end of the body 1 for purposes of mounting the ob- 80 servation platform as will be obvious from an inspection of Figs. 1 to 3.

When the hydroplane is traveling through the air, the rise and fall thereof is controlled by the side fins 9 pivoted as at 10 to 85 the sides of the body 1 and by adjusting the same to the full and dotted line positions shown in Fig. 3 the ascending and descending movement of the hydroplane is readily controlled. To provide for laterally steering 90 the hydroplane, side rudders 11 are pivotally mounted as at 12 to the opposite sides of the body 1 and are shiftable on the pivots 12 by the rods 13 projecting into the body and operable from within the same. 95

A parachute section is associated with each tubular support 5 to provide for a graceful descending movement of the hydroplane upon water, and also for safety purposes, each parachute section embodying a circular web 14 having bracing ribs 15 that are pivoted as at 16 to the arcuate brackets 17 secured exteriorly of the tubular supports 5 adjacent the upper ends thereof, the ribs 15 extending through slotted 105 openings 18 in the wall of the tubular supports as clearly shown in Fig. 4. The inoperative position of the parachutes is shown in Fig. 3, the webs 14 being positioned in inclosing relations relative to the adjacent 110 tubular supports.

To provide for the movement of the para-

chute sections to the operative position shown in Figs. 1 and 2, a longitudinal rod 19 is journaled in bearings 20 transversely of the tubular supports 5 adjacent the lower 5 face thereof with a rope drum 21 secured to each rod within the tubular supports as shown in Figs. 4 and 6. The ends 15' of the ribs 15 extending into the tubular supports 5 have cord connections 22 with a single 10 rope 23 that is wound on the reel 21. When it is desired to shift the parachute sections to the operative positions shown a crank 24 is applied to the key end 25 on one end of the shaft 19 to rotate the shaft and wind 15 upon the reels 21 the ropes 23, thereby moving downwardly the inner ends 15' of the ribs 15 and elevating the outer ends of the ribs with the parachutes 14 attached thereto. To hold the parachute sections in their 20 operative positions, a ratchet wheel 26 is fixed to the shaft 19 exteriorly of the tubular support 5 adjacent the crank end 25 and is adapted to be engaged by an overbalanced pawl 27 to prevent reverse movement of the 25 ratchet wheel 26 and to lock the shaft 19 in its said position. When it is desired to collapse the parachute sections the finger piece 27' of the pawl 27 is disengaged from the ratchet wheel 26 and by reversely rotating the shaft 19 the parachute sections 14 30 by their own weight will collapse and assume the position shown in Fig. 3.

It will therefore be seen that a safety 35 parachute attachment is provided for a hydroplane which will absolutely prevent a sudden descent of the machine while the observation platform 6 accessible by the ladder 8 is intended for use when the device is either in air or on water.

40 While there is herein shown and described the preferred embodiment of the present invention, it is nevertheless to be understood that minor changes may be made therein

without departing from the spirit and scope of the invention.

45

What is claimed as new is:—

1. A hydroplane comprising a body, a propeller at the forward end thereof, side fins and rudders carried by the body, parachute sections disposed above said body, 50 and an observation platform positioned above said parachute sections.

2. A hydroplane comprising a body, a propeller at the forward end thereof, side fins and rudders carried by the body, 55 parachute sections disposed above said body, perpendicular tubular supports carried by said body, a parachute section associated with each support, each parachute including a web section, radial ribs carried thereby and piv- 60 tally mounted on the tubular supports, a shaft journaled transversely of the tubular supports, and operative connections between said shaft and parachute ribs for moving the parachute sections to operative and in- 65 operative positions.

3. A hydroplane comprising a body, a propeller at the forward end thereof, side fins and rudders carried by the body, 70 parachute sections disposed above said body, perpendicular tubular supports carried by said body, a parachute section associated with each support, each parachute including a web section, radial ribs carried thereby 75 and pivotally mounted on the tubular supports, a shaft journaled transversely of the tubular supports, a rope reel within each tubular support fixed to said shaft projecting therefrom, and a rope connection between said reel and the parachute ribs 80 whereby reverse rotation of the shaft and rope reel will move the parachute section to operative and inoperative positions.

In testimony whereof I affix my signature.

JOHN CISON.
